UNITED STATES PATENT OFFICE

CLAUD H. EVERETT, OF LONDON, ENGLAND, ASSIGNOR OF ONE-HALF TO GEORGE
R. CARR, OF CHICAGO, ILLINOIS

STORAGE BATTERY

Application filed April 12, 1926. Serial No. 101,503.

My invention relates to gas vents for storage batteries and my object, while allowing all necessary freedom of escape or venting of gas in charging and discharging the battery is to prevent loss or wastage of the electrolyte and maintain the top of the battery jar in a dry state and thereby prevent grounds or leaks which are caused from a moist condition of the top surface of the battery jar. My invention therefore consists in the vent constructed as described by or included within the language of the appended claims.

In the accompanying drawing the figure is a vertical section of enough of a battery cell 13 to illustrate my invention.

Referring to the drawing 10 designates a jar having a hard rubber cover 11, this being of usual or any desired construction. Secured to the top, as by means of a hollow threaded neck 12 screwed into a hole perforating the top, is a cup 13 closed at the top by a cap 14 which is perforated with a number of small holes 15, for the escape to the atmosphere of gas entering the cup from the jar. Within the cup I place means in the nature of a filter device which allows the passage of gas but causes the condensation of free moisture accompanying the gas, which moisture being condensed trickles or runs back into the jar from the cup and thus loss of the electrolyte by evaporation of the water is diminished, and at the same time the discharge of aqueous vapor to and its condensation upon the top of the battery jar prevented so that a moist condition of its top surface from that cause is avoided. The condensing filter material I prefer to use is glass wool 16 that is supported within the cup by means of one or more perforated rubber plates or diaphragms, there being two such plates shown in the drawing spaced one above the other and thus I maintain the wool in its strata. By thus separating the mass of wool an ample quantity may be employed without danger of matting that would prevent free passage of the gas. I, of course, do not limit myself to this stratification of the wool altho I prefer it as an excellent arrangement.

What I claim is:

1. A vent for a battery jar comprising a

cup, means supporting the cup above the top of the jar, the interior of the cup having communication with the interior of the jar, a plurality of perforated diaphragms spaced one above another in the cup, and a filter medium 55 of loose parts upon each of such diaphragms.

2. A vent for battery jars comprising a cup, means supporting the cup wholly on the jar exterior, the interior of the cup being in communication with the interior of the jar, material in the cup whose parts are in a loose state with passages between them through which gas from the interior of the jar may pass, and means within the cup separating such material into strata one above another 60 and allowing the flow of gas from a lower stratum to an upper stratum.

In testimony whereof I hereunto affix my signature.
